UNITED STATES PATENT OFFICE

2,473,148

RADIATOR VALVE ASSEMBLY

August G. Joos, Velda Village, Mo., assignor to
Wagner Electric Corporation, St. Louis, Mo., a
corporation of Delaware

Application September 26, 1945, Serial No. 618,703

2 Claims. (Cl. 251—39)

1

This invention relates to valve mechanisms and in its more specific aspects is directed to a valve operating mechanism suitable for use on transformers.

The object of this invention is to provide a valve to close the openings leading to and from a transformer tank into one or more of its cooling radiators in order to interrupt the interchange of oil between the transformer and the radiators, thereby making it possible to remove the radiators from the transformer without any loss of oil in the transformer tank and to provide a quick, accurate, positive adjustment of the valve.

In the drawings:

Figure 1 is a plan view of a valve assembly;

Figure 2 is a sectional view showing the construction of certain details of the valve operating mechanism;

Figure 3 is a view taken substantially along the line 3—3 of Figure 2;

Figure 4 is a view of the valve similar to Figure 3 but in open position; and

Figure 5 shows the valve assembled on a transformer tank.

Large transformers are usually dismantled when shipped. This is particularly necessary with respect to the cooling radiators because they project from the transformer tank assembly and if allowed to remain thereon, would subject the same to the likelihood of breakage. It has been customary in the art to place a valve somewhere between the transformer tank and each of the radiators to facilitate dismantling and to enable disassembly of the radiators. Certain difficulties have arisen with respect to the use of these valves which subject them to leakage and difficulty of operation. This invention has been conceived, therefore, to overcome the difficulties of the prior art structures.

The objects and advantages set forth above are obtained in the structure shown in the several figures of the drawings in which numeral 1 is a section of a transformer tank to which a valve 2 is secured, as by welding. A fitting 3 is connected to the valve for supporting a radiator 4 through a suitable fixture 5 cooperating with fitting 3 which interiorly connects the radiator with the transformer tank. Fitting 3 is secured to the valve by means of a plurality of bolts 6 which are removed whenever it is necessary to disassemble radiator 4 from the transformer tank 1.

The valve 2 comprises a cylindrical body member 7 suitably apertured at 8 in which the movable valve member 9 is axially slidable. The movable member has a plurality of guides 10 thereon

2

which engage the wall of the aperture in order to guide the movement of the movable member. Sealing element 11 is secured to movable member 9 and is made from a suitable resilient material which is adapted to engage a valve seat 1a formed on member 7.

The movable member 9 is suitably bossed at 12 at substantially diametrically opposite positions, each of which bosses is tapped to receive studs 13 and 14. Each of the studs is locked into bosses 12 by means of lock nuts 15 and 16. Supported above the lock nuts are springs 17 and 18 and above the lock nuts is a bridge member 19 which rests on springs 17 and 18 and is held on the studs by nuts 20 and 21 which are locked on studs 13 and 14 by lock nuts 22 and 23.

Rotatably mounted in the body of the valve is a shaft 24 which extends to the exterior of body member 7 and on which a handle or crank 25 is mounted. The shaft is suitably supported and packed by means of a bushing 26 and a packing 27 to prevent the loss of oil in fitting 3 past shaft 24 when the valve is open. The body member 7 is provided with suitable apertures 28 and 29 which are adapted to selectively receive screw 30 threaded into the crank or handle 25. When the crank or handle 25 is turned to closed position, screw 30 is received in aperture 28 in order to lock the valve in closed position and when it is turned to open position, the screw is received in aperture 29 to lock the valve in open position.

In order to effect the opening and closing of the valve by means of the rotation of shaft 24, a pair of eccentrics 31 and 32 are provided thereon held apart by member 33. A collar 34 associated with the eccentric assembly has a conventional pin provided therein to lock it to the shaft so that it will hold the eccentrics in position. The proper adjustment of the valve is made by turning shaft 24 so that the valve is closed and then inserting screw 30 in aperture 28 and after this step has been accomplished, the lock nuts 22 and 23 are loosened whereupon nuts 20 and 21 are turned to apply proper pressure between member 11 and valve seat 1a to assure a tight, leakproof fit at this particular point. When this pressure has been applied, lock nuts 22 and 23 are tightened to lock the assembly in that adjustment. The springs 17 and 18 on studs 13 and 14 urge bridge member 19 into engagement with nuts 20 and 21 and insure the proper spacing between the bridging members and valve member. During subsequent openings and closings of the valve by rotating shaft 24 and crank 25, the valve will always be properly closed, thereby eliminating any possi-

bility of leakage at that point. The valve is shown in closed position in Figures 2 and 3 and in open position in Figure 4. When in closed position, the eccentrics 31 and 32 engage the inner surface of the head portion 19a of member 19 and when the valve is in open position, the eccentrics will engage the surface 9a of the movable member 9. As particularly shown in Figures 2, 3, and 4, the valve member is dished with the engageable surface 9a on the dished portion.

From the foregoing it is evident that a valve mechanism has been provided which is simple in its operation, positive in its action, and after adjustment will assure a perfect closure of the valve by obviating the necessity of an operator determining whether or not the valve is properly closed, this having been initially determined by the adjustment of the spacing between valve member 7 and bridge member 9 by nuts 20 and 21.

Having fully described my invention, that which I claim as novel and desire to protect by Letters Patent of the United States is:

1. A valve comprising a body member provided with a valve seat; a valve member having a portion engageable with said seat; a pair of 30 studs on said valve member; a bridging member provided with apertures through which the studs extend; resilient means associated with each stud to maintain said bridging member in predetermined spaced relation with said valve member; a shaft rotatably mounted in said body member and disposed between said bridging member and said valve member; eccentric means on said shaft engageable with said valve member to open the valve and engageable with said bridging member 35 to close the valve; and a nut on each stud in en-

5

gagement with said bridging member to adjust the spacing between said bridging member and said valve member to thereby adjust the pressure between the seat engaging portion of the valve member and said seat when the valve is in closed position.

2. A valve member comprising a body member provided with a valve seat; a valve member provided with a sealing member which is engageable with said valve seat; a pair of studs secured to said valve member; a bridging member provided with apertures through which said studs extend; a spring on each stud to space said bridging member from said valve member; a shaft rotatably mounted in said body member and disposed between said valve member and said bridging member; eccentrics on said shaft engageable with said bridging member to close the valve and engageable with said valve member to open the valve; and a nut on each stud in engagement with said bridging member to adjust the spacing between said bridging member and said valve member to thereby adjust the pressure between said seal and said valve seat when the valve is in closed position.

AUGUST G. JOOS.
